CONTINUOUS RETORTING OF OIL SHALE

Edward W. S. Nicholson and Lindsay I. Griffin,
 Jr., Baton Rouge, La., assignors to Standard
 Oil Development Company, a corporation of
 Delaware

Application June 21, 1949, Serial No. 100,314

2 Claims. (Cl. 202—23)

1

The present invention relates to the art of distilling oil-bearing minerals, such as oil shale, oil sands, tar sands and the like, maintained in the form of subdivided particles in a highly turbulent state, fluidized by upwardly flowing gases to resemble a boiling liquid, wherein the fresh charge undergoes rapid disintegration to form an excessive amount of particles having sizes below a properly fluidizable range. More particularly, the invention relates to improved means for maintaining properly fluidized beds of such materials during distillation.

Prior to the present invention, it has been proposed to carry out the distillation of oil shale in the form of subdivided solids varying in particle size from a fine powder up to rather large aggregates of, say, about $\frac{1}{4}$ inch diameter in a highly turbulent fluidized state. The heat required for distillation has been supplied either as sensible heat of preheated process materials, by indirect heat exchange of the fluidized bed with suitable heating means, by combustion of combustible shale constituents within the retorting zone, or as sensible heat of hot spent shale highly heated in a separate combustion zone and circulated to the fluidized bed in the retorting zone. The principal problem encountered in all these operations arises as the result of the strong tendency of the shale to disintegrate rapidly in the course of the distillation to particles having an extremely small size of about 0-20 microns which is the unit particle size of the shale silt. For example, Colorado shale when subjected to a fluid-type distillation quickly forms a mass containing about 60 per cent of fines of 0-20 microns size, and this even if the shale is charged with rather coarse aggregates. Attrition further increases the proportion of these fines in the highly turbulent or circulating solids masses. At the conditions of fluid shale distillation such fines tend to be entrained and carried overhead by the fluidizing gases. This situation is further aggravated by relatively frequent localized spurts or jets of gasiform materials caused in the fluidized bed by the flashing of water and oil from the cold fresh shale dropped into the hot fluidized bed. Even gas-solids separators of normally highest efficiency have been found inadequate to cope with this degree of solids entrainment. Aside from severe losses of valuable carbonaceous constituents removed from the distillation zone with these fines, the carry-over of excessive amounts of fines seriously complicates liquid product recovery due to heavy slurry formation and detri-

tally affects the fluidity of the fluidized bed which may be rapidly converted into a dilute phase which cannot be retained in the distillation zone unless special precautions are taken. 5 The present invention provides means for effectively counter-acting the detrimental effects of this type of fines entrainment.

In accordance with the present invention, losses of shale fines having particle sizes of 0-20 microns from a fluidized shale bed undergoing distillation, by entrainment and carry-over of the fines in the fluidizing gases and gasiform distillation products, may be materially reduced by obstructing the upward flow of the gases and entrained solids above the interface of the fluidized bed and within the distillation zone in such a manner that gasiform materials may pass the obstruction completely while a portion of the entrained solids is deflected back into the fluidized bed. This obstruction may have the form of inclined or horizontal off-set baffles prescribing a zig-zag flow for the solids-in-gas suspension, or of a non-fluidizable stationary packing having irregular passageways, or the like. However, 10 in accordance with a preferred embodiment of the invention the obstruction has the form of a horizontal perforated plate or grid capable of supporting a second fluidized solids mass and permitting entrained solid particles to penetrate the perforations so that a second fluidized bed of particles will form above the grid within a relatively short time of operation. Such fluidized solids, particularly when of a particle size slightly larger than 20 microns, have a strong capacity 15 for collecting fines of 0-20 microns size up to a concentration of about 30-50 per cent. More specifically, the invention provides, therefore, for the maintenance of a fluidized bed of solids supported by a horizontal grid plate above the interface of the fluidized shale bed undergoing distillation, wherein said second bed consists predominantly of solids having a particle size slightly 20 larger than 20 microns.

The formation of such a second fluidized bed 25 by direct carry-over of particles from the retorting bed is preferably supplemented by the addition of subdivided solids of the proper particle size by means other than immediate carry-over from the retorting bed. Another modification of this embodiment involves the supply to the second bed, of spent shale which has been subjected to combustion in a separate combustion zone for the purpose of generating the heat required for distillation.

30 The two fluidized beds are preferably connected

by a conventional downcomer pipe which permits flow of solids from the upper fluidized bed to the lower retorting bed. In this manner, a substantial proportion of the solids carried over from the retorting bed into the second bed may be returned to the retorting bed. In addition, the entire amount of heat-carrying burned shale recirculated from a separate combustion zone may be passed through the upper bed to the retorting bed and thus serve the dual purpose of preventing loss of shale fines from the distillation zone and supplying heat to the retorting bed.

Having set forth its objects and general nature, the invention will be best understood from the following more detailed description wherein reference will be made to the accompanying drawing in which:

Figure 1 is a schematical illustration of the basic concept of the invention;

Figure 2 is a similar illustration of a specific modification of the invention; and

Figure 3 illustrates in a similar manner the application of the invention to a conventional system including a retorting zone and a separate heat-generating combustion zone.

Referring now in detail to Figure 1, the numeral 10 designates a mostly conventional distillation vessel or retort adapted for fluid-type shale distillation and containing a fluidized shale bed M₁ supported by a gas distributing device, such as grid 12, and having a well defined interface L₁. Above this interface a second perforated grid 14 is provided. An overflow downcomer 16 leads from a point above grid 14 to a point below interface L₁.

In operation, fresh coarse shale, which may have a particle size of about 4-50 mesh, may be supplied through line 18 into the space between interface L₁ and grid 14. A fluidizing gas, such as steam, product tail gas, other inert gas, CO₂ and/or air, is supplied through line 20 and grid 12 at such a rate that a linear superficial gas velocity of about 0.5-3 ft. per second, suitable for fluidization, is established within bed M₁. Bed M₁ may be maintained at a distillation temperature of about 850°-1100° F. by any of the conventional methods described above which need not be specifically illustrated for a proper understanding of the invention.

The fresh shale upon entering bed M₁, undergoes distillation and disintegrates rapidly. As a result, bed M₁ may have a particle size distribution about as follows:

Size:	Weight per cent
0-20 microns	55
20-80 microns	10
80 microns-35 mesh	15
On 35 mesh	20

A portion of the entrained solids impinges on the imperforate portions of grid 14 and is thus returned to bed M₁. The remainder of the entrained solids penetrates the perforations of grid 14. Initially the fines of 0-20 microns size carried through grid 14 remain entrained in the gases and vapors and are carried therein to a gas-solids separator 22 in which a substantial proportion of the entrained fines, say, about 70 to 90%, may be separated. The separated fines may be likewise returned to bed M₁ via dip-pipe 24. The slightly coarser solids which have penetrated grid 14 gradually are building up thereon until they form a second fluidized bed M₂ having an interface L₂ above grid 14. Thereafter, a major pro-

portion of the fines penetrating grid 14 is retained in bed M₂, the remainder being carried into separator 22. Equilibrium of the system is established and maintained by overflowing and returning solids from bed M₂ via downcomer 16 to bed M₁ and withdrawing spent shale from bed M₁ through line 30. In this manner, about 80-99% of the solids leaving bed M₁ entrained in gases and vapors will be returned to bed M₁ via downcomer 16 and dip-pipe 24. Product vapors and gases are withdrawn through line 26.

A further improvement of the solids recovery in accordance with the invention may be accomplished by a system of the type illustrated in Figure 2.

Referring now to Figure 2, the system illustrated therein differs from that described with reference to Figure 1 essentially in the operation of the gas-solids separation system 22a, 22b, and 22c replacing separator 22 of Figure 1.

The operation of the system of Figure 2 is likewise analogous to that described with reference to Figure 1, system elements similar to those of Figure 1 being identified by like reference characters, with the exception of the gas-solids separation system. The gases and vapors containing entrained solids pass in series through cyclone separators 22a, 22b and 22c. The material separated in any one of these cyclones may be returned either to bed M₁ or bed M₂, as required to maintain the desired particle size distribution in bed M₂. In the example illustrated in Figure 2, the coarsest material which is separated in cyclone 22a and the finest material separated in cyclone 22c are both returned to bed M₁ while the particles of intermediate size separated in cyclone 22b are returned to bed M₂. Dip-pipes 24a, 24b and 24c are provided for this purpose. In this manner, bed M₂ is enriched in particles slightly larger than 20 microns size whereby the retention of fines of 0-20 microns particle size is favored.

As previously indicated, the invention has particular advantages when used in connection with a system wherein hot spent shale is circulated from a separate combustion zone to the retorting zone for the purposes of heat supply. A system specifically adapted to the application of the invention is illustrated in Figure 3 wherein like reference characters are used to identify system elements similar to those of Figures 1 and 2.

Referring now to Figure 3, there is shown a fluidized combustion zone or burner 50 in addition to the elements of Figure 1. Spent shale withdrawn through line 38 from bed M₁ may be passed to line 35 and suspended therein in air sufficiently preheated to support combustion of the shale. The air is supplied at a rate sufficient to carry the spent shale through grid 52 into burner 50, to substantially completely burn the carbon off the spent shale at a temperature about 50°-300° F. higher than that in retort 10, and to maintain a superficial gas velocity within burner 50 of about 1-3 ft. per second adequate to establish a fluidized mass M₅₀ of burning shale having an interface L₅₀ within burner 50. The gas containing entrained shale fines passes overhead into separator 54 from which separated solids may be returned to mass M₅₀ through dip-pipe 56. Flue gas of low solids content may be vented through line 58.

Burned spent shale is withdrawn from bed M₅₀ through an aerated standpipe 60 or the like and passed substantially at the temperature of mass M₅₀ to bed M₂ in retort 10. The circulation rate

of hot shale through line 60 depends on the temperature differential between burner 59 and bed M₁. A ratio of burned, hot shale to fresh shale charged of about 5-20:1 is usually adequate for the purposes of heat supply. Approximately the same solids circulation rate is maintained in lines 30 and 35 to establish equilibrium. Excess solids may be withdrawn from burner 59 through line 62.

The particle size distribution of the solids circulating through line 60 may be about the same as that specified for bed M₁ of Figure 1.

In addition to containing material coarser than 20 microns, these particles are low in carbon or practically carbon-free and have, therefore, a substantially lower gas buoyancy than the high carbon particles of similar size which are entrained and carried overhead from bed M₁. The burned shale particles supplied through line 60 to retort 10 above grid 14 are, therefore, ideally suited to form a well fluidized, relatively dense bed of solids, M₂, above grid 14, adapted to retain substantial proportions of fines entrained from bed M₁ and penetrating grid 14. The hot solids then flow through downcomer 16 to supply the heat required in retorting bed M₁ and to repeat the cycle described above. As a result of the extremely high circulation rate of hot low-carbon solids from burner 59, bed M₂ will at all times consist predominantly of particles of sufficiently low gas buoyancy to retain an adequate proportion of the fines of 0-20 microns size entering bed M₂ from bed M₁.

When operating in the manner last described, the fines concentration of the effluent of retort 10 leaving through line 26 will be substantially less than in the absence of a second bed M₂.

Various modifications of the systems illustrated may appear to those skilled in the art without deviating from the spirit of the invention.

The above description and exemplary operations have served to illustrate specific embodiments of the invention but are not intended to be limiting in scope.

What is claimed is:

1. In the process of distilling oil-bearing minerals of the type of oil shale, which disintegrate when subjected to distillation, in the form of a dense turbulent mass of subdivided solids

fluidized by an upwardly flowing gasiform medium to form a well defined interface within a distillation zone at a distillation temperature, the improvement which comprises partially obstructing the free upward flow of said medium containing entrained solids within the distillation zone by a flow obstruction arranged at a level above said interface, passing said medium upwardly over the entire height of said distillation zone past said obstruction, forming above said obstruction a second fluidized mass of solids consisting predominantly of retorted mineral particles from which at least a major proportion of residual carbon has been removed by combustion and which have a size slightly larger than 20 microns diameter, passing said medium containing fully entrained solids particles upwardly from said second mass through a multi-stage gas-solids separation zone, classifying said fully entrained particles in said separation zone into a first fraction of particles of a size larger than said slightly larger particles, a second fraction of particles of said slightly larger size and a third fraction of particles not exceeding 20 microns in size, returning said first fraction to said first-named mass, returning said second fraction to said second mass and returning at least a portion of said third fraction to said first-named mass.

2. The process of claim 1 in which retorted mineral particles are continuously circulated from said first-named mass to a separate fluid-type combustion zone, subjected to combustion therein and returned to said second mass.

EDWARD W. S. NICHOLSON.
